UNITED STATES PATENT OFFICE.

JOHN C. DUNCAN, OF PITTSBURGH, PENNSYLVANIA.

HACKSAW.

1,292,275.

Specification of Letters Patent.

Patented Jan. 21, 1919.

Application filed March 21, 1917. Serial No. 156,815.

To all whom it may concern:

Be it known that I, JOHN C. DUNCAN, a citizen of the United States, and resident of Pittsburgh, in the county of Allegheny and 5 State of Pennsylvania, have invented certain new and useful Improvements in Hacksaws, of which the following is a specification.

One object of the invention is to provide 10 improved means for adjustably securing the blade to the saw frame, a primary purpose in this connection being to provide a construction wherein the adjusting device cooperates with a frame formed of metal of 15 rectangular cross-section, avoiding the necessity of providing the frame with a socket for rotatably confining the blade holding device as is usual with hacksaws now in general use.

20 A further object is to provide improved means for securing the saw blade with its cutting edge disposed either in the plane of the frame arch, or at right angles thereto as may be desired, the blade being secured 25 in either position without rotating the devices to which either end of the blade is secured. The exact location of the blade in either position in which it is to be used is thus accurately predetermined and is not 30 varied by turning or rotating the holding means for either end of the blade.

Further objects of the invention are to 35 provide improved means for securing the blade ends whereby accurate positioning and holding of the blade will be assured; to provide an adjustable frame of improved construction for accommodating blades of different lengths; and for extending the blade-holding frame arms for depending the saw 40 frame arch.

In the accompanying drawings, Figure 1 is a side elevation of a hacksaw constructed in accordance with the present invention, and Fig. 2 is a bottom edge view of the 45 same. Fig. 2^a is a detail of a portion of one of the blade-holding arms. Figs. 2^b and 2^c are similar views showing a slight modification. Fig. 3 is a sectional elevation of the connection between the adjustable frame 50 arm and the back bar, and Fig. 4 is a cross section of the same taken on line 4—4 of Fig. 1. Fig. 5 is a sectional detail of the adjustable blade securing device and a portion of the handle for adjusting the same. 55 Fig. 6 is a sectional detail of the blade adjusting device taken on line 6—6 of Fig. 5.

Fig. 7 is an inner end view of the blade adjusting device. Fig. 8 is an elevation of the hacksaw provided with arm extensions for carrying the blade and handle. Fig. 9 60 is a sectional detail taken on line 9—9 of Fig. 8, and Fig. 10 is a cross section taken on line 10—10 of Fig. 8.

Referring to the drawings, 2 designates the 65 back bar of the saw frame from which project the spaced arms 3 and 4 between which are secured the saw blade 5. Back bar 2 and at least one of arms 3 are preferably formed of a single piece of metal of rectangular cross section, and the other arm 4, here shown adjustably secured to the back 70 bar for accommodating blades of different lengths, is also of similar cross section.

The means for adjustably securing the 75 blade to arm 3 whereby the tension of the blade is regulated comprises a stem-like holding device 6 which is longitudinally slotted between its ends at 7 for slidably embracing arm 3, being held in position on the latter by removable stops or cleats 8. 80 The outer end of device 6 is threaded at 9 for engagement with the internally threaded portion 10 of handle 11, and is provided with washer 11' having an angular hole to pass stem 6, said washer being adapted to 85 bear against frame arm 3 for exerting the required pull or tension on the holding device when tightening up the blade. With the blade holding and adjusting means of 90 the construction here shown, it is unnecessary to form the frame arm with a socket for rotatably confining such device as has been the practice heretofore, thereby materially cheapening the cost and providing a 95 stronger construction. Also with the holding means non-rotatable, it is always in accurate position for holding the blade with its cutting edge disposed accurately either in the plane of the arch, or at right angles thereto, depending on the character of the 100 work being done. The improved construction simplifies the blade adjusting or blade changing operations, changes being made more expeditiously and with less effort than with hacksaws now in general use.

105 The saw blade is provided with perforations adjacent its opposite ends for engaging pins 12, 12' carried by arm 4 and similarly disposed pins 13, 13' carried by the inner end of holding device 6. Pins 12 and 110 13 project laterally from the frame for holding the blade with its cutting edge in the

plane of the arch, as in Figs. 1 and 4, and pins 12' and 13' are utilized for holding the blade with its cutting edge at right angles to the plane of the arch. With the 5 blade in engagement with either pair of pins, tightening of the holding device 6 by turning handle 11 results in placing the blade under the required tension. To insure holding the blade very accurately in the plane 10 in which it is to operate, the face 14 from which pin 13 projects is inclined in such manner as to recede backwardly or inwardly from its outer extremity, and pin 13 projects from said face in a backwardly inclined direction. The same construction is 15 characteristic of face 14 from which pin 13' extends, and is also true of the side face and end face of arm 4 from which pins 12 and 12' project as shown at 14^a and 14^b. Instead of placing the last mentioned pins 20 in arm 4, they may be carried by the lateral extension 4^a of said arm, with the extension provided with the sloping faces as in Figs. 2^b and 2^c. The result is that the 25 extremities of the blade when hooked over the appropriate pins and placed under tension are deflected in such manner as to insure tight engagement of the blade with the extremities of the sloping faces, the inclination of the pins forcing the blade extremities into flat engagement with the sloping faces and causing the blade to tightly stretch over the edges of said faces in the manner described, thereby insuring accurate and 30 permanent alinement of the blade. Furthermore, the outer or higher extremity of face 14, or 14' is preferably notched to provide bearing points 15 against which the blade bears when under tension, thereby still further insuring its accurate position, as in 35 Figs. 5 and 7.

For adjustably securing arm 4 to back bar 2, the bar embracing sleeve-like portion 4' of said arm is formed with the transverse 45 circular pin passage 16 which is adapted to register with one or another of the curved notches 2' in the edge of bar 2, so that when passage 16 and one of the notches are in alinement, a through circular passage is 50 formed, whereas when they are not in alinement, pin passage 16 is intersected by the back bar. A pin 17 rotatable in passage 16 is partially circular and partially flat, as shown in Figs. 1, 3 and 4, with the result 55 that when the circular portion is turned into engagement with one of notches 2', arm 4 is locked on the back bar, whereas when the

pin is turned to place its flat surface 17 toward the back bar, the latter is disengaged and arm 4 is free to slide thereon in either 60 direction.

For increasing the depth of the frame arch and thereby adapting the same for use on relatively deep or thick work in which an arch of considerable expanse is required, 65 the blade carrying arms are provided with extension pieces 18 as in Figs. 8, 9 and 10, one of these pieces splicing onto the side face of arm 4 on which there are no blade-holding pins, and the other piece is similarly 70 secured to the face of arm 3 back of stops 8. Each of pieces 18 carries an arm-embracing socket 19, the open side of which may be closed by the swinging catch 20 which is secured in closed position by the 75 set screw 20'. One of the extension pieces is provided with pins 12^a and 12^b for securing the outer end of the blade, and the other extension piece is provided with removable stops 8^a for slidably confining the 80 blade holder 6. To change from the arrangement shown in Fig. 1 to that in Fig. 8, it is only necessary to relax and detach the blade and then remove the lowermost stop 8, whereupon the adjustable blade-holding 85 device may be removed, and then after the extension pieces 18 have been applied, the blade and its holding device may be mounted on the extremities thereof as in Fig. 8, exactly the same way as when the 90 extension pieces are not in use.

I claim:—

In a hacksaw and in combination with a saw blade having perforated ends, a frame having supporting arms one of which is 95 provided with two saw contacting faces constructed so as to stand at an angle to the major or active portion of the saw when in position thereon, a movable support carried by the other arm and provided with two saw contacting faces each of which stands at an angle to the major or active portion of the saw when in contact therewith, pins 100 projecting from said saw contacting faces and inclined thereto, and a handle screw 105 threaded to said movable support and arranged to vary the tension on said blade.

In testimony whereof I affix my signature in presence of two witnesses.

JOHN C. DUNCAN.
